UNITED STATES PATENT OFFICE.

CARL HUSS AND FRITZ TOURNEY, OF NEW YORK, N. Y., ASSIGNEES TO A. HOLLANDER
& SON, INC., A CORPORATION OF DELAWARE.

FUR-GROOVING MACHINE.

Application filed October 25, 1927. Serial No. 228,653.

Our invention relates to a machine for forming grooves or stripes in fur by cutting the hair on given lines for the purpose of simulating a fur article made up from 5 a series of small skins, or for ornamental purposes.

The general object of our invention is to provide a novel and practical machine for producing grooves or stripes as referred to.

10 The nature of our invention, its distinguishing features and advantages will clearly appear as the description proceeds.

Reference is to be had to the accompanying drawings, it being understood that the 15 drawings are merely illustrative as examples of the invention.

Figure 1 is a plan view of a fur grooving machine embodying our invention;

Figure 2 is a front view thereof with 20 portions broken out and sectioned;

Figure 3 is a fragmentary view, in transverse vertical section, showing the fur carrier with the fur in position approaching the cutting means;

25 Figure 4 is an enlarged view in detail, the view being generally similar to Figure 3 but showing the fur in the act of being cut to form grooves;

Figure 5 is a diagrammatic front elevation 30 showing a modification;

Figure 6 is a plan view of a fragment of fur after the grooves have been formed therein; and

Figure 7 is an enlarged view, in cross 35 section, given to better indicate the grooves.

In carrying out our invention in practice in accordance with the illustrative example, a suitable frame 10 is provided, on the top 11 of which is a bed 12, adjustable forward and back by means which in the illustrated example are as follows: An angle bracket 13 is secured to the top 11 as by bolts 14. A screw 15 passes through the upstanding member of said bracket 13 and its forward 40 end has threaded engagement with the bed 12 at the rear edge. The screw 15 adjacent the bed 12 has a set nut 16, and set nuts 17, 18 are disposed on the screw at opposite sides of bracket 13, said nuts serving to hold the screws 15 and bed 12 in adjusted 45 position.

The bed 12 at the front has a depending bracket 19 inclined to a vertical plane, said depending bracket 19 having a forwardly 50 extending foot 20. On the bed 12 at the

bracket portion 19 is supported a series of bed knives or counter knives 21 which pass through an upper securing bar 22 and a lower securing bar 23 on the face of bracket 19, said bars 22 and 23 having, respectively, 55 binding screws 24, 25. Each bar 22, 23 has openings 26 through which the bed knives or fixed knives 21 pass. Also passing through the depending bracket 19 from the back thereof through the front are adjusting screws 27 bearing against the knives 21 at the back. Additional adjusting screws 127 pass upwardly through the foot 20 and bear against the lower end of the knives 21. The adjusting screws 15, 27 and 60 127 serve to adjust the knives 21 relatively to the paths of the cutting edges of revolving cutter means, shown in Figures 1 to 4 as in the form of revolving toothed cutter wheels 28. The screws 24 and 25 serve to 65 fasten the knives 21 in adjusted position.

The cutters 28 are keyed on a shaft 29, turning in bearing brackets 30 on frame 10, and said cutters 28 are spaced the desired distance apart by washers or spacing collars 70 31 on shaft 29 which are slipped onto or from the shaft or arbor 29. The shaft 29 is driven by any suitable means, being shown as a drive pulley 32, which in practice is adapted to receive power from any 75 convenient source.

The means provided to feed the fur A to the cutter means, and in illustrated example is advantageously employed, is an endless traveling carrier belt 33 turning about suitable rollers, one of which rollers, designated 80 34, is adjacent to the cutting edges of the knives 21 and the teeth of the cutters 28. The cutting means is so arranged as to form grooves in the fur, for which purpose the 85 cutters 28, in the example shown in Figures 1 to 4, are spaced the distance at which it is desired to form the grooves. As the fur is caused to move with the belt 33 about the elongated pulley 34 the fur is caused to be 90 disposed radially by said pulley and in a manner to extend beyond the rotary path of movement of the cutting edges of the cutters 28. As said fur continues to travel it wipes past the cutting edges of the cutters 21 so 95 that the cutters 28, which revolve more rapidly than the speed of the feed of the fur by the belt 33, serve to cut grooves in the fur, the depth of the groove being the desired depth to which the cutter means and 100 105 110

the roller 34 is adjusted. Said roller 34 turns in bearings in slide blocks 35 supported by angle brackets 36 on the frame 10. The bearing blocks 35 are held adjustably by bolts or screws 135 passing through slots 235 in said blocks.

In the form shown in Figure 5, a cutter, designated generally by the numeral 40, has spiral blades 41 which revolve in a path to 10 coact with the fixed knives or bed knives 121 by any suitable clamping means, there being shown a clamping bar 122, it being understood that the knives 121 are fastened and adjusted in the same manner as the 15 knives 21.

Any desired number of cutting elements may be employed as desired to produce a particular number of grooves or stripes.

We would state furthermore that while 20 the illustrated examples constitute practical embodiments of our invention, we do not limit ourselves strictly to the exact details herein illustrated, since, manifestly, the same can be considerably varied without departure 25 from the spirit of the invention as defined in the appended claims.

We claim:

1. A fur grooving machine including driven grooving knives, bed knives coacting 30 with the grooving knives, and feed means to carry the fur to be grooved to a point to be acted upon by said cutting knives.

2. A fur grooving machine including fixed bed knives, revolving cutter means 35 coacting with said bed knives, the bed knives being spaced a predetermined distance apart according to the distance at which the grooves are to be spaced.

3. A fur grooving machine including

fixed bed knives, revolving cutter means 40 coacting with said bed knives, the bed knives being spaced a predetermined distance apart according to the distance at which the 45 grooves are to be spaced, and a traveling fur carrier.

4. A fur grooving machine including a frame, a bed adjustable on said frame, separate spaced bed knives supported on said bed, cutter means coacting with said bed 50 knives to groove the fur, and means to adjust said bed on the frame.

5. A fur grooving machine including a frame, a bed adjustable on said frame, separate spaced bed knives supported on said bed, cutter means coacting with said bed 55 knives to groove the fur, and means to adjust said bed on the frame, together with means to adjust the bed knives lengthwise and transversely.

6. A fur grooving machine including a 60 frame, a bed adjustable on said frame, separate spaced bed knives supported on said bed, cutter means coacting with said bed knives to groove the fur, means to adjust said bed on the frame, together with means 65 to adjust the bed knives lengthwise and transversely, and set screws to hold the bed knives in adjusted position.

7. In a fur grooving machine, a frame, a bed adjustable on said frame, a depending 70 bracket on said bed, separate spaced knives supported on said bracket, means to adjust the knives on the bracket, and cutter means coacting with the bed knives to form grooves in the fur.

CARL HUSS.
FRITZ TOURNOY.
